BOX HOLDER

Filed Aug. 29, 1928

UNITED STATES PATENT OFFICE

WILLIAM L. HOOD, OF LEXINGTON, MASSACHUSETTS

BOX HOLDER

Application filed August 29, 1928. Serial No. 302,835.

This invention relates to holders for shoe polish boxes and the like, and its object is to provide a novel and improved device of that nature having, among others, the advantages hereinafter described and illustrated.

In the drawing of one embodiment of my invention selected for illustration and description herein,

- 10 Fig. 1 is a plan;
 Fig. 2, a side elevation;
 Fig. 3, a partial vertical section on the line 3—3, Fig. 1;
 Fig. 4, a cross vertical section on the line 15 4—4, Fig. 2;

Fig. 5, a development of one form of the spring member for closing the cover; and

- 20 Figs. 6 and 7 respectively, plans of the strap and clip hereinafter described.

25 Referring first to Figs. 1, 2, my novel box holder comprises a handle *a*, fashioned to provide parallel bars or rods 1, 2, of convenient length and suitable material, as metal.

The outer or free ends of the bars are curved to provide box holding and engaging arms 3, 4, which, Fig. 3, may be sprung to receive the body of the box 5, and then closed to grasp it securely.

30 To lock the arms 3, 4, around the box 5, Fig. 1, the members 1, 2, are provided with a strap 6 which extends from one bar to the other and is slidable thereon, and has its ends curved about them thus locking them in position.

35 The strap 6, Fig. 2, may be a separate piece, Fig. 7, and secured to the spring 7, Fig. 2, or it may be fashioned from arms 12, Fig. 5, integral with the spring 7 and rolled about the rods 1, 2.

40 The cover 8 is preferably made larger than any box likely to be secured in the holder, so that it can provide for a variation in the size of the box within certain limits, and is 45 provided with a sheet of suitable material as thin rubber, paper, cloth or any material that is more or less compressible, so that it can act under pressure of the spring 9 to seal the joint between the box and cover as a protection against the admission of air to pre-

vent the drying and hardening of the contents of the box.

The finger piece 9, Fig. 2, may be secured to the spring 7 as by a clip 10, Fig. 6, as a separate member, or if preferred, by fashioning the spring 7, Fig. 5, to form laterally extended arms 11, 11, which may be folded inwardly and about the finger piece extension 9 to lock it to the adjacent spring portion 7. In this case it will be observed that the spring and finger piece are integral as in Fig. 5.

In use, the arms 3, 4 are sprung apart sufficiently to receive the desired box 5, the arms 3, 4, locking the box in position, with the cover 8 resting thereon, the original box cover being discarded. The cover 8 will be pressed down upon the box 5 sufficiently hard to effectually close it by the spring 7, and obviously the cover may be raised at will by pressure of the thumb upon the finger piece 9, Fig. 3.

50 My novel holder is convenient, inexpensive, and provides a novel self-closing omnibus box cover that will preserve the box contents and yet permit free access thereto.

55 My invention is not restricted to the precise embodiment thereof described and illustrated, but is more particularly pointed out in the following claim.

Claim:

A box holder comprising a pair of relatively movable box gripping arms, a lock therefor, a cover for the box, a finger piece on the cover for raising and lowering the cover, a resilient support and spring for the finger piece comprising a strap like member with arms on each side thereof, one pair of arms being coiled about the box gripping arms to form said lock, the strap like member being coiled to form said support and spring for the finger piece, and a second pair of arms secured to said finger piece.

60 In testimony whereof, I have signed my name to this specification.

WILLIAM L. HOOD.
